UNITED STATES PATENT OFFICE.

WINTER W. MYERS, OF BROOKLYN, NEW YORK, ASSIGNOR TO AUSTRAL WINDOW COMPANY, OF NEW YORK, N. Y., A CORPORATION OF MAINE.

BALANCED WINDOW.

1,359,095.

Specification of Letters Patent. Patented Nov. 16, 1920.

Application filed January 26, 1917. Serial No. 144,595.

To all whom it may concern:

Be it known that I, WINTER W. MYERS, a citizen of the United States, residing at Brooklyn, in the county of Kings and State of New York, have invented certain new and useful Improvements in Balanced Windows, of which the following is a full, clear, and exact description.

The invention which constitutes the subject matter of this application relates to improvements upon what is commonly known as the "Austral" window.

Referring to the drawings:

Figure 1 is a vertical section through the casing and sashes of a balanced window taken at right angles to the plane of the window.

Fig. 2 is a vertical section taken in the plane of the window.

Fig. 3 is a detail section of a portion of the window illustrating the mode of attachment of the detachable portion of the parting strip.

Fig. 4 is a section, similar to Fig. 1, illustrating the position of the parts when the sashes are in open position.

Fig. 5 is a section taken on line 5—5 of Fig. 2.

Fig. 6 is a section taken on line 6—6 of Fig. 2.

Fig. 7 is an enlarged view of the sash guiding means.

Fig. 8 is a spring metal backing for the member supporting the lower guide roller.

Referring to the drawing in detail, the reference characters 10, 11 and 12 designate the upper, side and lower portions of a hollow metal jamb for a window which is of the "Austral" type, and in which are mounted the upper sash 13 and the lower sash 14 balanced on the arms 15 (only one being shown), as will be understood.

The vertical side portions of the jamb are provided on the interior thereof with grooves 16, preferably of rectangular shape, which are adapted to receive correspondingly shaped parting strips 17 and 18 riveted to the hollow jamb or otherwise secured in said groove. The parting strip 17 for the side jamb is provided with a weather strip 19 projecting outwardly from and at right angles to the plane of the window, and the upper sash 13 is provided with a groove 20 to receive the weather strip 19,

the upper portion of the groove being enlarged so that the sash may be readily assembled when it has been reversed for cleaning or other purposes. The lower parting strip 18 is provided with a corresponding flange or weather strip 21 adapted to enter 60 into a corresponding groove 22, but this groove is not enlarged, although adapted to be so, since the method of removing or reversing this sash is somewhat different from the reversing, assembling or removal of the 65 upper sash, as will appear later on.

As will be apparent from Figs. 5 and 6, the jambs are preferably offset, as indicated at 23, and this serves to prevent either of the sashes from falling outwardly, thereby 70 avoiding injury to the sashes or to the pedestrians below. This is particularly true with respect to the upper sash, which is reversed for cleaning or adapted to be entirely removed by taking out the removable strip portion 24 of the parting strip, as will be understood. The portion 24 of the parting strip is held in place by its upper end engaging under a flange 25 of the main parting strip and by means of the 80 slide 26 entering a socket 27 in the pivot block 28.

The upper sash is provided with a guide roller 29, which is preferably mounted on an angle-iron 30 (see Fig. 6) secured to the 85 face of the said sash. This guide roller has a loose fit in the parting strip in which it is adapted to move upwardly and downwardly. The upper jamb is provided with a boss 31, extending across the top, which serves as a 90 parting strip at this end. Extending across the top of the jamb is a bead 32 provided with a cam surface which engages with the outer and upper edge 33 of the upper sash in such fashion that during the final closing movement the latter is cammed inwardly 95 so as to enable it to make a weather-tight engagement with the various parting strips.

The guide roller 34 for the lower sash is fixed to a member 35 (see Figs. 5, 7 and 8). 100 slidably mounted upon the base plate 41 of the said sash. When it is desired to reverse or remove the lower sash the guide roller is merely withdrawn from the groove of the parting strip 18. The member is held in 105 fixed position by suitable means, such as rivets 36. To slide the member 35 it is only necessary to direct a pull upon the finger

piece 39 to move it beyond the end of spring plate 40. This spring plate is fixed upon the base plate 41.

The base 12 of the window jamb is provided with an upwardly projecting boss 37, the lower edge of the sash being correspondingly recessed to fit over this boss. On the base there is provided a cam surface 38 which serves to force the lower sash, during its closing movement, in weather-tight engagement with the parting strips.

What I claim is:—

1. In a window of the class described, the combination of upper and lower sashes, of a frame therefor provided with grooved parting strips against which each of said sashes normally engages, balancing levers connected at their ends to the upper and lower sashes, and guide means on said sashes for engaging the grooves in the parting strips to guide the sashes and permit them to swing on their pivots and assume angular positions with respect to the frame.

2. In a window of the kind described, the combination with upper and lower sashes, of a frame therefor provided with parting members, balancing levers pivoted to the frame and having their ends pivotally connected to the upper and lower sashes respectively, weather stripping provided between said parting members and one or both of said sashes, and guides attached to said sashes for slidably engaging said parting members to guide the sashes and permit them to swing on their pivots and assume angular positions with respect to the frame.

3. In a window of the class described, the combination with upper and lower sashes, of a frame therefor provided with a parting strip against which said sashes normally engage, balancing levers connected at their ends to the upper and lower sashes, guide means for said sashes slidably engaging said parting strip, and coöperating means on said sashes and parting strip for effecting a weather-tight engagement between the same.

4. In a window of the class described, the

combination with upper and lower sashes, of a frame therefor provided with a grooved parting strip against which said sashes normally engage, balancing levers connected at their ends to the upper and lower sashes, guide means for said sashes engaging said grooved parting strip, and a flange and groove connection between the sashes and parting strip for effecting a weather-tight engagement between the same.

5. In a window of the class described, the combination with upper and lower sashes, of a frame therefor provided with grooved parting strips against which each of said sashes normally engages, balancing levers connected at their ends to the upper and lower sashes, guide means on each of said sashes for slidably engaging said parting strips, one of which is adapted to be moved laterally of its sash and out of the corresponding path of the grooved parting strip and a flange and groove connection between the sashes and parting strip for effecting a weather-tight engagement between the same.

6. In a window of the class described, the combination with upper and lower sashes, of a frame therefor provided with grooved parting strips, a section of which is adapted to be removed to permit the release from the said grooves of the slidably engaging means upon one of the sashes, each of said sashes normally engaging said parting strips, balancing levers connected at their ends to the upper and lower sashes, guide means on each of said sashes for slidably engaging said parting strips, one of which is adapted to be moved laterally of its sash and out of the path of the corresponding grooved parting strip, and a flange and groove connection between the sashes and parting strips for effecting a weather-tight engagement between the same.

In testimony whereof I affix my signature.

WINTER W. MYERS.
